UNITED STATES PATENT OFFICE.

CLESSON A. LOWELL AND EDWARD R. BROWN, OF SOMERVILLE,
MASSACHUSETTS.

AIR-COMPRESSING APPARATUS.

SPECIFICATION forming part of Letters Patent No. 618,959, dated February 7, 1899.

Application filed September 17, 1897. Serial No. 652,031. (No model.)

To all whom it may concern:

Be it known that we, CLESSON A. LOWELL and EDWARD R. BROWN, of Somerville, in the county of Middlesex and State of Massachusetts, have invented certain new and useful Improvements in Air-Compressing Apparatus, of which the following is a specification.

One object of this invention is to obtain automatically an unlimited number of successive charges of compressed air by means of water admitted to a closed receptacle or tank under pressure.

Another object is to control automatically the admission of water under pressure to said receptacle or tank in order to prevent excessive waste of water.

These and other objects are accomplished by mechanism hereinafter described.

Our invention consists of certain novel features hereinafter described, and particularly pointed out in the claims.

In the accompanying drawings, which illustrate a construction embodying our invention, Figure 1 represents a vertical longitudinal section through the apparatus. Fig. 2 is an enlarged sectional view of the device for controlling the admission of water under pressure to the closed tank.

Like letters of reference refer to like parts throughout both views.

The metal tank A, which is preferably cylindrical in shape, is supported by suitable feet A' and has a bottom plate A² and is provided with a cap or cover B, which provides room for some of the working parts and is of reduced transverse section to avoid too much idle air-space within the tank. At the top of the cap B is the outlet C for the compressed air and to which is secured the cap C', and leading from said cap C' is a suitable pipe C². This air-outlet is preferably controlled by means of a check-valve C³, above which is located the ball C⁴, supported by the lugs C⁵ on the inner side of the cap C'. The water-inlet pipe D enters through the bottom plate A² of the tank and is provided with a suitable water-regulator D'. Also connected to said bottom plate A² is a water-outlet pipe E of considerably greater diameter than the

water-inlet pipe D. This water-outlet pipe E is controlled by the valve E', attached to a rod F and adapted to be guided in its movements by the guides E² and E³.

On the rod F there is mounted the float G, 55 which is adapted to slide vertically on said rod, and its downward movement is limited by the contact of the boss G' with the top of the valve E', and its upward movement is limited by the contact of the boss G' with the 60 shoulder F' of the enlarged portion F² of the rod F. The upper portion of the rod F terminates in the curved finger F³, thus forming a seat for the float H in its lowest position. The transverse supporting-piece I extends across the tank A near the top, and by means of a downwardly-depending hanger I' supports the lever J, which is pivoted to said hanger at K and is also pivotally connected at one end to the upper portion F² of the rod 7c F, as shown at K', and is pivotally connected at the other end at K² to the rod L, hereinafter described.

Within the cap B is located the pipe H', 75 communicating with the air and leading upward to the top of said cap B. This pipe serves alternately as a temporary discharge-passage for the compressed air and as an inlet-pipe for another charge of air and will be designated as the "air inlet" and "exhaust" 80 pipe. At its upper end this pipe carries the bracket H² and the bifurcated guide-piece H³. To the bracket H² there is pivotally connected at H⁴ the rod H⁵, which carries the float H, and said rod is guided by the bifurcated guide-piece H³. The upper end of the pipe H' is controlled by the valve H⁶, carried by the rod H⁵. When the outlet-valve E' is closed and the rod F and curved finger F³ are in their lowest positions, the float H is in 90 its lowest position and rests in the curved finger F³ and the valve H⁶ is closed. With the parts in their normal positions, as shown in Fig. 1, the water, entering through the pipe D, gradually fills the tank A until the float G 95 is raised until the boss G' strikes the shoulder F'; but the buoyancy of the float G is not sufficient to lift the rod F against the internal pressure of the compressed air, the tendency of which is to hold the valve E' upon its 100

seat and close the water-outlet pipe E. When, however, the water rises sufficiently in the tank A to partially submerge and raise the float H, the air-pressure is relieved by the 5 opening of the valve H⁶, and the float G is sufficiently buoyant to lift the rod F and open the valve E' to allow the discharge of the water from the tank A.

One end of the lever J is bifurcated at J', 10 and within the bifurcations is located one end J² of the bell-crank lever J³, which is journaled at J⁴ in the support J⁵, secured to the side of the tank A, and the upper end of said bell-crank lever is provided with the 15 weight J⁶, the office of which is to hold the valve E' down upon its seat and the outlet-pipe E closed until the float H rises, as hereinbefore described, in which case the rod F, being lifted by the float G, will, through the 20 bifurcated end J, throw the weight J⁶ to the right beyond its center of support J⁴, and thus hold the valves E' and H⁶ open. As the water escapes from the tank A through the outlet-pipe E the float G gradually falls until 25 there is only sufficient water to submerge about one-third of said float G, in which case the weight of said float bearing on the valve E' will force said valve E' to its seat and close the outlet-pipe E, and in said movement the 30 rod F, descending, will, through the forked end J' of the lever J, move the weight J⁶ to the left of its center of support J⁴ and the finger F³ and the float H will descend, thereby closing the valve H⁶ and preventing further inlet of air which has been passing into the 35 tank during the time that the valve E' was open to allow the discharge of water.

The rod L, which is pivotally connected at K² to one end of the lever J, extends downwardly within the tank A and is pivotally secured at L' to the plunger L² and is provided with the stem L³, which is guided in its movements by the guide L⁴. This plunger L² controls the admission of water under 40 pressure into said tank A from the pipe D. The water-controlling device M consists of the upper and lower parts M' and M², screwed together, as shown, with a suitable packing L⁵ between the parts. The upper part M' is 45 provided with a vertical passage M³, which terminates in two passages M⁵ in the lower part M² and opening within the tank A. In the upper part M' is a chamber M⁶, surrounding the passage M³, and said chamber M⁶ 50 communicates with said passage M³ by the circular slot M⁴, formed in the pipe L⁶ and communicating with the chamber M⁶. With the parts in the position shown in Fig. 1 the water enters through the pipe D under 55 pressure, passes up through the opening N, through the branch passages M⁷ to the chamber M⁶, and said plunger L² is in the position shown in Fig. 2, and the water passes through the slot M⁴ down through the passage M³ and 60 out by the passages M⁵ into the tank A. As the water continues to pour into the tank A, the air within the tank A is compressed, and 65

this compressed air is let off through the outlet-pipe C² and used for any desired purpose—for instance, forcing liquids through pipes. 70 As the water rises within the tank A the float G rises, as hereinbefore described. The further rising of the water completely submerges the float H, and when the water has submerged the float to the proper extent the buoyancy of 75 the float H is sufficient to open the valve H⁶ against the internal air-pressure, and upon the opening of said valve H⁶ the residue of the compressed air escapes through the pipe H', and owing to the reduction of air-pressure a sudden rising of the water occurs. The internal air-pressure being thus relieved, the float G immediately lifts and opens the valve E' against the weight J⁶, which normally tends to hold said valve E' closed. 80 When the float G lifts the rod F and opens the valve E', as described, and throws the weight J⁶ to the right of its center of support, the forked end J' of the lever J, moving upwardly with the rod F, causes the opposite 85 end K of said lever J to move the rod L downwardly and the plunger L² to close the slot M⁴, and thereby prevents the passage of water through the pipe D into the tank A.

From the above it will be seen that when 90 the valve E' is lifted and the outlet-pipe E open for the passage of water from the tank A no inlet of water to the tank A can take place, owing to the plunger L² closing the slot M⁴ in the pipe L⁶, so that only the water within the tank escapes by the outlet-pipe E, because no additional water can enter the tank A through the pipe D, owing to the plunger L² preventing the entrance of water to the tank. By thus preventing any entrance of 95 additional water to the tank it is obvious that considerable water is saved from waste, and, further, the water is discharged much quicker than if additional water were being poured into the tank through the inlet-pipe, even 100 though the area of the inlet-pipe may be considerably less than the area of the outlet-pipe. When the valve E' closes, as described, by reason of the weight of the float G, the rod F in descending moves downwardly the forked 105 end J' of the lever J and moves the weight J⁶ to the left of its center of support, as shown in Fig. 1, and in the descent of the forked end J' of the lever J the opposite end K³ of said lever is caused to rise and move upwardly the 110 rod L, and the plunger L², which, moving upwardly, opens the slot M⁴ and permits the passage of water from the pipe D into the tank A through the passage M⁷, chamber M⁶, slot M⁴, 115 passages M³ and M⁵, and the water, rising in 120 the tank A, compresses the air, which passes off through the pipe C², and the operation of the apparatus is repeated, as previously described.

The ball C, which rests on the lugs C⁵, does 125 not interfere with the passage of the air to the pipe C², as the air passes around said ball and lugs; but the object of said ball is for the purpose of closing the pipe C² in the event

of the water, owing to the escape of the air through the pipe H', rising too suddenly by the relief of the pressure and filling the cap B. In this case the water would lift the ball C⁴ and close the pipe C², whereby no water could pass from the apparatus, and upon the descent of the water the ball C⁴ would fall to its normal position on the lugs C⁵.

Although the float H in its lowest position is shown as resting in the finger F³, yet it will be understood that it is not necessary for it to rest in said finger, as said float would be supported in its lowest position by reason of the valve H⁶, secured to the rod H⁵, closing the pipe H', and also by reason of the pivotal connection H⁴ of said rod H⁵.

By the above apparatus there is economically produced successive charges of compressed air by means of water admitted under pressure to a closed receptacle, and the amount of water used for such purpose is controlled as hereinbefore set forth.

We do not limit ourselves to the arrangement and construction shown, as the same may be varied without departing from the spirit of our invention.

Having thus ascertained the nature of our invention and set forth a construction embodying the same, what we claim as new, and desire to secure by Letters Patent of the United States, is—

1. In an air-compressing apparatus, a closed tank, a water-inlet, a valve controlling said water-inlet, a water-outlet, a valve controlling said water-outlet, an air-inlet, a valve controlling said air-inlet, an air-outlet, a valve controlling said air-outlet, a lever pivoted intermediate of its ends, a rod connecting one end of said lever with said valve controlling the water-inlet, a rod connecting the other end of said lever with said valve controlling the water-outlet, a float adapted to slide on said rod connected with the valve controlling the water-outlet, and a mechanism connected with an end of said lever to normally hold said end in either an elevated or a depressed position.

2. In an air-compressing apparatus, a closed

tank, a water-inlet, a valve controlling said water-inlet, a water-outlet, a valve controlling said water-outlet, an air-inlet, a valve controlling said air-inlet, an air-outlet, a valve controlling said air-outlet, a lever pivoted intermediate of its ends and having one of its ends bifurcated, a rod connecting one end of said lever with said valve controlling the water-inlet, a rod connecting the other end of said lever with said valve controlling the water-outlet, a float adapted to slide on said rod connected with the valve controlling the water-outlet, and a bell-crank pivoted at its angle and having one of its legs projecting upwardly from the pivotal point and having the other leg engaging with the bifurcation in said lever, and a weight carried by said upwardly-projecting leg of the bell-crank.

3. In an air-compressing apparatus, a closed tank, a water-inlet, a valve controlling said water-inlet, a water-outlet, a valve controlling said water-outlet, an air-inlet, a valve controlling said air-inlet, an air-outlet, a valve controlling said air-outlet, a lever pivoted intermediate of its ends, a rod connecting one end of said lever with said valve controlling the water-inlet, a rod connecting the other end of said lever with said valve controlling the water-outlet, a float adapted to slide on said rod connected with the valve controlling the water-outlet, a rest carried by said rod on which the float is mounted, a pivoted lever connected with said valve controlling the air-inlet, a float carried by said lever connected with the air-inlet and adapted to register with said rest, and means for normally holding an end of said lever in either an elevated or a depressed position.

In testimony whereof we have signed our names to this specification, in the presence of two subscribing witnesses, this 11th day of September, A. D. 1897.
